UNITED STATES PATENT OFFICE

ERNEST COHN, OF INDIANAPOLIS, INDIANA, ASSIGNOR TO TURNER GLASS CORPORATION, OF TERRE HAUTE, INDIANA, A CORPORATION OF INDIANA

DESIGN FOR A JAR OR SIMILAR CONTAINER

Application filed May 12, 1930. Serial No. 35,590. Term of patent 14 years.

To all whom it may concern:

Be it known that I, ERNEST COHN, a citizen of the United States, residing at Indianapolis, in the county of Marion and State of Indiana, have invented a new, original, and ornamental Design for a Jar or Similar Container, of which the following is a specification, reference being had to the accompanying drawing, forming part thereof.

Fig. 1 is a horizontal section, looking down, taken substantially on the line 4—4 of Fig. 2.

Figs. 2 and 3 are elevations of a container showing my new design, the two figures being taken from slightly different viewpoints.

I claim:

The ornamental design for a jar or similar container as shown.

ERNEST COHN.
